DESIGN FOR A FACE PLATE FOR ARTICLE OF JEWELRY

Michael Chernow, New York, N. Y.

Application April 11, 1941, Serial No. 100,317

Term of patent 7 years

To all whom it may concern:

Be it known that I, Michael Chernow, a citizen of the United States and residing at New York, in the county of New York and State of New York, have invented a new, original, and ornamental Design for Face Plates for Articles of Jewelry, of which the following is a specification, reference being had to the accompanying drawing, forming part thereof, and in which:

Fig. 1 is a front elevational view of a face plate for an article of jewelry showing my new design,

Fig. 2 is a top view, and

Fig. 3 is a side view.

I claim:

The ornamental design for a face plate for an article of jewelry, substantially as shown.

MICHAEL CHERNOW.
